[57] **CLAIM**

The ornamental design for a drain clip for weather strip of automobile, as shown and described.

DESCRIPTION

FIG. 1 is a top plan view of a drain clip for weather strip of automobile showing our new design;

FIG. 2 is a front elevational view thereof;

FIG. 3 is a bottom plan view thereof;

FIG. 4 is a rear elevational view thereof;

FIG. 5 is a right side elevational view, the left side elevational view being a mirror image thereof;

FIG. 6 is a sectional view taken along the line 6—6 in FIG. 2;

FIG. 7 is a sectional view taken along the line 7—7 in FIG. 2;

FIG. 8 is a perspective view of the bottom rear and one side thereof; and,

FIG. 9 is a side elevational view in conjunction with a weather strip and automobile body panel shown in broken sectional lines.

The broken lines shown in the view of FIG. 9 are for illustrative purposes only and form no part of the claimed design.
